(57) **CLAIM**

The ornamental design for an applicator cover, as shown and described.

DESCRIPTION

FIG. 1 is a top, perspective view of an applicator cover;
FIG. 2 is a front view thereof;
FIG. 3 is a rear view thereof;
FIG. 4 is a left side view thereof;
FIG. 5 is a right side view thereof;
FIG. 6 is a top view thereof; and,
FIG. 7 is a bottom view thereof.
The subject matter shown in dashed lines, and any surfaces
of the design not shown, form no part of the claimed
invention.
